Patented Sept. 25, 1928.

UNITED STATES PATENT OFFICE.

OTTO WEISKOPF, OF ERFURT, GERMANY.

TENS-CARRYING DEVICE FOR CALCULATING MACHINES.

Application filed May 1, 1926, Serial No. 106,110, and in Germany May 5, 1925.

My invention relates to calculating machines and more especially to a single-stage tens-carrying device which is directly operated without special preparation by the tens 5 tooth of each dial wheel, but in which the parts of the tens-carrying device are not in constant mesh with the pinions of the dial wheels. The new device is particularly suitable for a calculating machine having a single key board in which by depressing the numeral keys the items indicated are directly transferred to the counter without actuating cranks or levers.

The device should move easily so that it is 15 operated without effort but, on the other hand, it should not be liable to overrun. It is an object of my invention to provide a tens-carrying device which combines easy running with reliability.

20 To this end I provide toothed sectors for connecting the single tooth of one dial wheel with the pinion of the adjacent dial wheel, and I suspend these sectors for oscillation on rocking levers which are operated by the 25 denominational slide of the machine so as to raise said sectors into and to lower them out of mesh with the teeth and pinions of the dial wheels. By this arrangement the sectors are not held in constant mesh and the 30 inner resistance is reduced to a minimum. Checks are provided against overrunning of the sectors, these checks being so arranged that the sectors can be oscillated only through an angle corresponding to a single tooth.

35 When the rocking levers are lowered into their initial position, their sectors get out of mesh with the teeth of the dial wheel teeth and pinions and are returned to their normal position by gravity or by means of a light 40 spring.

In the drawings affixed to this specification and forming part thereof a tens-carrying device embodying my invention is illustrated diagrammatically by way of example.

45 In the drawings

Fig. 1 is an elevation of a portion of the device, partly in section on the line 1—1 in Fig. 2,

Fig. 2 is a section on the line 2—2 in Fig. 1,

Fig. 3 is a section on the line 3—3 in Fig. 2,

Figs. 4, 5 and 6 are detail illustrations of rocking levers.

Referring to the drawings, 60 is a stationary shaft mounted in the casing 1 of the 55 calculating mechanism, 61 are the dial wheels and 62 are spring catches which cooperate

with notches on these wheels. 63 is the driving wheel which can be displaced on a shaft 28 by means of a pin 75' at the denominational slide 75. The driving wheel 63 meshes 60 with pinions 64 on the dial wheels 61, each pinion having ten teeth. Opposite the pinions single teeth 65 are provided on each dial wheel. 68 are rocking levers fulcrumed on a pin 69 in the casing 1, and 66 are toothed sectors 65 adapted to oscillate on pins 67 in the levers 68. Each sector is adapted to mesh with the tooth 65 of each dial wheel 61, and at the same time with the pinion 64 of the dial wheel at the left which corresponds to a 70 higher denomination.

The number of sectors 66 and rocking levers 68 corresponds to the number of denominational orders less one for which the mechanism is designed. Each segment is free to 75 oscillate about its pin 67 between shoulders 76 and 77 of the levers 68. The downward motion of the levers 68 is limited by a stationary bar 70. When the levers are resting on this bar, the sectors 66 are not in mesh 80 with the pinions 64 and the teeth 65.

Means are provided for raising all levers 85 68 to the left of a given lever when such lever is raised while those at the right of the lever are not raised. This is effected by pins 71 in the levers which are adapted to enter holes 72 or slots 73 in the adjacent lever. In each pair of adjacent levers, as shown in Fig. 3, the pins 71 are alternately inserted 90 near the upper and near the lower edge of the levers, respectively. Each pin 71 projects into the hole 72 or into the slot 73 of the adjacent lever so that, when a lever 68 is raised, the levers which are at the left of the said lever, will be raised with it, whereas the 95 levers at its right will not be raised. In this manner the tens-carrying device is operated correctly for rotation of the dial wheels to the left and to the right.

A recess 66' is formed in each sector 66 100 above the pin 67, so that its upper end is lighter than the lower end, and a bar 74 is inserted in this recess so as to prevent oscillation of the sectors for more than a single tooth to the right and the left. Therefore 105 the tens-carrying device is limited to a single tooth and overrunning is reliably prevented.

Rocking of the levers is effected by a V-shaped cam 75' at the rear end of the denominational slide 75 which is adapted to be reciprocated on bars 31 by suitable mechanism, connected with the tabulator keys, (not

shown), and coupled with the driving wheel 33 by the pin 75'. Pins 68^a at the ends of the levers are engaged by the cam 75^a. When the denominational slide is displaced to the left into the position corresponding to the first denominational order to be calculated, the cam 75^a will raise all levers at the left of the denominational slide. Those levers which are released by the cam return to their initial positions by their pins 68^a sliding down on the cam 75^a at the right, but all levers at the left of the denominational slide will remain in raised position and will keep their sectors 66 engaged with the pinions 64 of the dial wheels.

When a numeral key is depressed, the denominational slide 75 automatically moves to the right the distance corresponding to one denominational order, raising the lever 68 which is at its right, and so on for each denominational order, until the last lever at the right has been released by the cam 75. Only after this has occurred, all levers 68 will drop, causing all sectors 66 to be disengaged from the pinions 64 and the teeth 65. The sectors which are out of mesh resume their vertical position under the action of their weighted lower ends, but, as mentioned, springs may be provided for adjusting said sectors.

I wish it to be understood that I do not desire to be limited to the exact details of construction shown and described, for obvious modifications will occur to a person skilled in the art.

I claim:

1. Single stage tens-carrying device for calculating machines comprising, a denominational slide, dial wheels, a pinion and a single tooth connected with each dial wheel, weighted arms mounted below said dial wheels for free rocking motion, toothed sectors forming part of said arms and adapted to connect the single tooth of one dial wheel with the pinion of the adjacent dial wheel, means for limiting the stroke of said sectors so as to prevent overrunning and means connected with said denominational slide for

throwing said sectors into and out of mesh with said pinions and teeth on said dial 50 wheels.

2. Single stage tens-carrying device for calculating machines comprising, a denominational slide, dial wheels, a pinion and a single tooth connected with each dial wheel, 55 a rocking lever for each dial wheel, weighted arms mounted below said dial wheels for free rocking motion on said levers, toothed sectors forming part of said arms and adapted to connect the single tooth of one dial wheel 60 with a pinion of the adjacent dial wheel and pivotally carried on said levers and a cam on said denominational slide adapted to rock said sector-carrying levers.

3. Single stage tens-carrying device for 65 calculating machines comprising, a denominational slide, dial wheels, a pinion and a single tooth connected with each dial wheel, a rocking lever for each dial wheel, weighted arms mounted below said dial wheels for 70 free rocking motion on said levers, toothed sectors forming part of said arms and adapted to connect the single tooth of one dial wheel 75 with a pinion of the adjacent dial wheel and pivotally carried on said levers, 75 and a V-shaped cam on said denominational slide adapted to rock said sector-carrying levers.

4. Single stage tens-carrying device for calculating machines comprising, a denominational slide, dial wheels, a pinion and a single tooth connected with each dial wheel, 80 a rocking lever below each dial wheel, a weighted arm mounted on each lever for free rocking motion, a toothed sector forming 85 part of each arm and adapted to connect the single tooth of one dial wheel with a pinion of the adjacent dial wheel, means carried on said denominational slide for rocking said levers, and a connection between said levers 90 causing each lever, when raised by said decade slide, to raise the lever on its left but not the lever on its right.

In testimony whereof I affix my signature.

OTTO WEISKOPF.
